CLAIM

The ornamental design for a vibrator, as shown and described.

DESCRIPTION

FIG. 1 is a top, front and right side perspective view of a vibrator showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1;

FIG. 11 is an enlarged view of portion 11 in FIG. 2;

FIG. 12 is an enlarged view of portion 12 in FIG. 3;

FIG. 13 is an enlarged view of portion 13 in FIG. 5;

FIG. 14 is a front, top and right side perspective view showing the vibrator in a disassembled state;

FIG. 15 is a front, top and right side perspective view showing the vibrator in a stretched state; and,

FIG. 16 is an enlarged view of portion 16 in FIG. 15.

The dash-dot broken lines shown in FIGS. 9, 10, 11, 12, 13, 15 and 16 are for the purposes of showing enlarged areas and form no part of the claimed design.

The broken lines in the drawings illustrate portions of the vibrator which form no part of the claimed design.

1 Claim, 16 Drawing Sheets
